STEAK PLATTER

Joe P. Bowlin, Fort Worth, Tex.

Application May 12, 1953, Serial No. 24,962

Term of patent 14 years

(Cl. D44—10)

To all whom it may concern:

Be it known that I, Joe P. Bowlin, a citizen of the United States, residing at Fort Worth, in the county of Tarrant and State of Texas, have invented a new, original, and ornamental Design for a Steak Platter, of which the following is a specification; reference being had to the accompanying drawing, forming part thereof.

In the drawing:

The essential features of my design reside in those portions shown in full lines.

I claim:

The ornamental design for a steak platter, as shown and described.
